(57) **CLAIM**

The ornamental design for a cosmetic tube container, as shown and described.

DESCRIPTION

FIG. 1 is a perspective view of a cosmetic tube container showing my new design;

FIG. 2 is a front elevation view thereof;

FIG. 3 is a rear elevation view thereof;

FIG. 4 is a left side view thereof;

FIG. 5 is a right side view thereof;

FIG. 6 is an enlarged top plan view thereof; and,

FIG. 7 is an enlarged bottom plan view thereof.

(Continued)

The broken lines in the drawings depict portions of the cosmetic tube container that form no part of the claimed design.

1 Claim, 7 Drawing Sheets
